HORIZONTAL BREAK DISCONNECTING SWITCH

Application filed April 30, 1930. Serial No. 448,510.

This invention relates to disconnect switches, and more particularly to such switches as are adapted for outdoor use, and preferably gang operation.

Switches of the kind here contemplated generally comprise a supporting base which is preferably grounded and upon which is mounted a contact supporting insulator and one or more switch-blade-supporting or actuating insulators. In some types of switches the contact supporting insulator is rotatable while in other types it is stationary. With increasing voltages the required spacing of the contact and the blade from one another and the spacing of both from the supporting base becomes very great. The insulators may be more than eight feet long and the blade may be more than twelve feet long. The insulator stacks are generally made of porcelain or other frangible material and therefore are not able to withstand high stresses, especially in bending. Disconnect switches are infrequently operated, being required to stand perhaps for years in a given position, during which time they are exposed to all sorts of adverse weather. While the switch is closed, the contact and the end of the switch blade in engagement therewith may become corroded together. They may also become covered with sleet or ice. The difficulty of swinging a blade over twelve feet long and mounted on an insulator over eight feet long, when the free end of the blade is held to its contact by ice, sleet, and corrosion may be readily appreciated. Unless means is provided to break the bind between the blade and the contact any turning effort applied to the blade actuating insulator may cause cracking of the insulator. In the prior art with which we are familiar this has been done by exerting either a longitudinal or a twisting motion to the blade prior to the swinging thereof away from the contact. This is not quite satisfactory in that it induces certain cantilever or bending stresses in the blade actuating insulator. In addition, if the bind between the blade and the contact is strong the contact may be drawn with the blade in its longitudinal movement

thus causing bending and possible cracking of the contact supporting insulator. Other forms of ice breaking movements have been developed wherein the contact as well as the blade are actuated to break the bind between them. These constructions of the past have been such that bending of the contact supporting insulator is not avoided in the event that the parts are rigidly frozen together, thereby again subjecting the insulator to the danger of cracking.

It is one of the objects of the present invention to provide a high voltage disconnect switch having a powerful ice breaking movement and wherein the bending stresses in the insulators are reduced to a minimum or entirely eliminated. This is accomplished in the embodiments of our invention herein illustrated by making the contact supporting insulator rotatable and providing engagement between the contact and the blade on the opposite sides of the axis of rotation of the contact. To open the switch the contact is first turned so as to twist the same free of any bind between it and the blade, and then the blade is swung to the open position. Due to the fact that the contact is engaged by the blade on the opposite sides of its axis of rotation and preferably at equal distances from its axis of rotation the bending stress in the contact supporting insulator is eliminated. During this ice breaking movement the switch blade may be maintained stationary or it may be given a slight reciprocating or oscillating movement to assist in breaking the bind between it and the contact.

The contacts are preferably of the pressure area type. The design is such as to obtain as much contact area as possible. When this is done the pressure need not be tremendously high in order to carry say 600 amperes continuously. The contacting ends of the blade and contact are so constructed as to relieve the pressure between them when the contact is rotated to open the switch, thereby relieving the switch blade and its supporting insulator of the stress otherwise incident to the overcoming of this pressure when the switch

95

90

100

is to be opened. The contact design is such that the full contact area and pressure will be obtained even though lost motion should develop in the operating mechanism.

- 5 This is accomplished, in the embodiment herein illustrated, by making one of the contact engaging portions U-shaped and moving it to embrace the other contact, after which one of the contacts is twisted or
 10 turned into firm engagement with the other. As shown the U-shaped contact is mounted at the end of the switch blade and is adapted to receive its cooperating contact between its arms. This may be reversed without departing from the spirit or scope of the present invention.

In our pending application Serial No. 419,776, filed January 10, 1930, we show a switch of the type above described wherein
 20 the switch blade swings in a vertical plane, the supporting insulators also extending vertically. In the switch shown in that application the axis of rotation of the blade extends at right angles to the axis of rotation
 25 of its actuating insulator and also at right angles to the axis of rotation of the contact which is engaged by the blade. The present invention is more particularly concerned with a horizontal break switch, that is, one where-
 30 in the switch blade moves in a substantially horizontal plane. The plane of motion of the blade is at right angles to the axes of rotation of the respective rotatable insula-
 35 tors rather than coincident with these axes as in the case of the vertical break switch. This introduces a special problem in the de-
 sign of the contacts so that the engagement between the end of the switch blade and the contact may take place upon the oppo-
 40 site sides of the axis of rotation of the rotary contact. We overcome this difficulty in the embodiment of the invention herein illustrated, by making the contacting end of the blade in the form of a fork or prong
 45 the tines of which extend horizontally and at right angles to the blade. The cooperat-
 ing contact comprises a substantially rect-
 50 angular vertically extending bar. This arrangement may be reversed if desired.
 55 When the switch is closed the rectangular contact is disposed between the tines of the prong and with its larger side reaching be-
 60 tween the tines. To open the switch the blade is maintained stationary while the con-
 tact is rotated through an angle to bring the larger side of the rectangular contact into a position at right angles to the tines of the prong. The axis of rotation of the contact (or of the prong if the construction is
 65 such that the rectangular contact is mount-
 ed on the switch blade) is coincident with the axis of rotation of its actuating insulator which axis extends midway between the contacting edges, hence there is no tendency
 70 to produce bending stresses in the actuating

insulator. By this arrangement even if the contact and the blade are frozen fast there will be no tendency to pull or thrust the switch blade supporting insulator.

As previously stated, the blade support- 70 ing insulator and the contact supporting insulator are both rotatable. We prefer to use a common actuating means for rotating both of the insulators. The driving means is preferably connected to the blade sup- 75 porting insulator and a driving connection is established between this insulator and the contact supporting insulator. It is essential that substantially no positive driving force be applied to the switch blade during the 80 initial or ice breaking movement of the contact. To accomplish this end a lost motion is introduced in the connection between the blade and its actuating insulator. Spring means is provided for taking up this lost 85 motion after the switch blade commences to move. While we prefer to locate the lost motion directly between the blade and its supporting and actuating insulator this may be altered if desired. For instance, the 90 blade may be mounted upon its supporting insulator without any lost motion, and lost motion may be introduced between the insulator and the means for actuating the 95 same.

The attainment of the above and further objects of the present invention will be apparent from the following specification taken in conjunction with the accompanying drawings illustrating a few preferred em- 100 bodiments of our invention.

In the drawings:

Figure 1 is a side view of a switch con-
 105 structed in accordance with our invention;

Figure 2 is a plan view thereof;

Figure 3 is a fragmentary sectional view
 110 showing the manner of supporting the switch blade upon the rotary insulator;

Figure 4 is a fragmentary sectional view
 115 taken along the line 4—4 of Figure 3;

Figure 5 is a diagrammatic view showing
 120 the manner of operation of the switch operating cranks;

Figure 6 is a similar diagrammatic view
 125 showing the corresponding operation of the switch contact and of the switch blade; and

Figure 7 is a side view of a modified form
 130 of switch constructed in accordance with our invention.

Reference may now be had more particu- 120 larly to Figures 1 and 2. The switch shown in these figures comprises a grounded sup-
 125 porting base 1 which may be of any stand-
 ard construction. As shown, this base com-
 130 prises an inverted channel member. A cen-
 tral insulator stack 2 is rotatably mounted
 upon the base by means of a suitable bear-
 ing 3 which is preferably of a construction
 such as shown in the pending application of
 Alfred Alsaker, Serial No. 137,926, filed 130

September 27, 1926, although it is to be understood that any other preferred form of bearing may be used if desired. The insulator stack 2 comprises a number of petic-
 5 coat insulators 4 of a construction well known in the art and secured together in the usual manner. Each insulator is shown as including an insulator pin 5 for mounting the insulator and an insulator cap 6 secured to the top of the insulator for facilitating the mounting of something upon the insulator. The insulator pin of the bottom insulator of the stack 2 is secured to the rotatable element of the bearing 3 in a manner such as is shown in the above referred to application of Alfred Alsaker, and the bearing itself is secured to the channel base 1 in any approved manner, such for instance as shown in that application. A switch
 10 blade 10 is mounted upon the top of insulator section 4 of the insulator stack 2 in a manner such as is shown more particularly in Figures 3 and 4 to which reference will be made as the description proceeds. It may
 15 be sufficient to state for the present that this switch blade is not rigid with respect to the insulator stack but that the insulator stack is permitted a limited degree of motion without affecting the blade 10, but that
 20 further rotation of the insulator stack 2 will bring about a rotation of the blade 10.

A pair of insulator stacks 15 and 16 are rotatably mounted upon the channel base 1 by means of bearings 17 and 18, respectively, which bearings may be of a construction such as the bearing 3. The insulator stacks 15 and 16 may be of any approved construction and have been illustrated as of the same type as the insulator stack 2. The lower section of the insulator 15 is provided with an insulator pin 20 for mounting the same, and the upper portion of the insulator stack 15 is provided with an insulator cap 21 for providing a support for a contact and a line terminal. Likewise the insulator stack 16 is provided with an insulator pin 24 and an insulator cap 25 for a like purpose. A spindle 30 is suitably bolted to the insulator cap 25 and passes through a cylindrical shell 31 supported thereby. The shell 31 is rotatively mounted upon the member 30 so that upon rotation of the member 30 the shell 31 need not rotate. The shell 31 provides a support for a line terminal 32 which is secured thereto and which is adapted to receive a line wire. The spindle 30 extends through the shell 31 and has a contact 35 secured thereto or formed integrally therewith. Thus the contact 35 rotates with the insulator stack 16. A flexible conductor 37 connects the terminal 32 with the contact 35.

The contact 35 is adapted to cooperate with a contact 40 carried by the end of the blade 10. The contact 40 is U-shaped, and
 60 is adapted to receive the contact 35 between

the arms thereof. The contact 35 is provided with two contacting faces 41 and 42 for engaging the arms of the contact 40. The contact 35 is mounted centrally of the insulator stack 16 so that the axis of rotation of the insulator stack, which is necessarily also the axis of rotation of the contact 35, passes through the center of the contact thereby placing the contacting faces 41 and 42 on the opposite sides of the axis of rotation of the contact 35 and at equal distances from the axis of rotation. As a result when the contact 35 is rotated with respect to the contact 40 to break any bond that may have formed between the two this contact 35 does not tend to swing the blade 10 in either direction. This is a distinct improvement over switches of the past with which we are familiar and wherein the contact as well as the blade is rotated in that in the prior switches the rotation of the contact corresponding to the contact 35 tends to draw the switch blade with it. Hence, in such construction, if there is a strong bond between the contact and the switch blade, as may result from corrosion or the formation of an excessive amount of ice upon the switch, rotation of the contact will tend to draw the switch blade with it thereby producing stresses in the supporting insulators. These stresses may, and frequently do, become so great as to crack the supporting insulators. This is avoided by our improved construction.

The insulator stack 15 is provided with a contact identical to the contact 35 and with a line terminal identical to the terminal 32. At the end of the switch blade adjacent the insulator stack 15 there is provided a contact 40' identical with the contact 40 at the opposite end of the switch blade. The contacts 40 and 40' face in opposite directions as may be clearly seen from Figure 2.

To open the switch the three insulator stacks 2, 15 and 16 are simultaneously rotated in a manner to be more fully set forth as the description proceeds. As previously stated, a lost motion is introduced between the insulator stack 2 and the blade 10 so that upon the initial rotation of this insulator stack the blade may remain stationary while the contacts are rotating. The manner of mounting the switch blade upon its supporting insulator whereby this lost motion is obtained is shown in Figures 3 and 4 to which reference may now be had. A spindle 50 having a base 51 is secured to the insulator cap 6 of the top insulator section 4 of the central insulator stack 2. The base 51 may be secured to the cap 6 in any preferred manner as by means of suitable bolts or the like. The spindle 50 passes through an opening in a blade holder 53 which rests upon the spindle and is freely rotatable thereon. A coiled spring 55 encircles the

spindle between the blade holder 53 and the base of the spindle. One end of the spring 55 bears against a pin 56 which is secured to the base of the spindle 50 whereas the 5 other end of the spring bears against a pin 57 which is secured to the blade holder 53. Except for the spring the blade holder 53 is free to remain stationary during the rotation of the spindle. If desired this 10 amount of rotation may be limited to about fifteen or twenty degrees by the location of a suitable stop upon the spindle 50 which stop engages a cooperating stop upon the blade holder 53 after a relative rotation between the two of about fifteen degrees. Such abutment means may take the form of a pin 58 driven into the spindle 50 above the spring 55 and abutting against the pin 57 after a predetermined rotation of the 15 spindle 50 in the switch opening direction in the event that the blade is not released prior to the abutment of the pin 58 against the pin 57. This abutment means may of course be omitted if desired.

20 The central insulator stack 2 is rotated by means of a crank 60 which is secured to the rotatable member of the bearing 3. While this crank may be of any approved construction we prefer to use a crank of the kind 25 shown in the pending application of Alfred Alsaker and Elias S. Corneliusen, Serial No. 378,337, filed July 15, 1929. The rotatable portion of the bearing has a part thereof extending beyond the body of the bearing 30 which part is of octagonal or other non-circular shape and to which the crank 60 is clamped. The crank may be secured to the bearing in any adjusted position thereof. The crank 60 is rotated by the usual switch 35 operating mechanism in a manner well known in the art and forming no part of the present invention. A pair of cranks 61 and 40 62 are secured to the rotatable member of the bearing so as to be rotated therewith.

45 The crank 61 is connected to the rotatable member of the bearing 17 by means of a connecting rod 63 and a crank 64. In a like manner the crank 62 is connected to the rotatable member of the bearing 18 by means 50 of a connecting rod 65 and a crank 66. The cranks 64 and 66 may each be of a construction such as is shown in the pending application of Alfred Alsaker and Elias S. Corneliusen above referred to, although any 55 other preferred form of crank may be used if desired. It may thus be seen that upon actuation of the crank 60 to rotate the center insulator stack 2 a turning moment is applied to the cranks 64 and 66 thus rotating the insulators 15 and 16 and with them the 60 associated contacts 35.

65 A description will now be given of the manner of operation of the switch when the crank 60 is manipulated to open it, and for this purpose reference may be had to Figures 5

and 6 which show the position of the various operating parts when the switch is closed. These figures show only the right hand half of the switch of Figure 1 it being understood that the left hand half of this switch 70 operates in exactly the same manner. When the switch is in the closed position the crank 62, the crank 66 and the connecting rod 65 are all in the position indicated by the full lines in Figure 5. At this time the switch blade and the contact in engagement therewith are in the relative positions indicated in Figure 6. To open the switch the insulator 2 must be rotated in a clockwise direction as seen in Figure 2, hence the crank 75 62 of Figure 5 is rotated in a clockwise direction. Assume a uniform rotation of the crank 62. The free or driving end of the crank 62 moves from its closed position at "a" to its open position at "e" passing 80 through the intermediate positions "b", "c", and "d". As the crank 62 moves from the position "a" to the position "d" the crank 66 is rotated in a counter clockwise direction from the position "a" to the position "d". 85 At the position "d" the crank 62 and the connection rod 65 are in alignment; hence the position "d" is the extreme position for the crank 66. Further rotation of the crank 62 from the position "d" to the position "e" 90 results in a reversal of the direction of rotation of the crank 66 which now is turned in a clockwise direction to the position indicated at "e" for the crank 66. As previously stated the crank 66 is locked to the rotatable element of the bearing 18 to which the insulator stack 16 is bolted, hence the insulator stack 16 and with it the contact 35 have an angular motion identical with the motion of the crank 66. The contact 35 is 95 thus rotated from the position shown in full lines on Figure 6 in a counter-clockwise direction through the positions "b" and "c" to the position indicated at "d" and thereafter it is rotated in the opposite direction to the position indicated at "e". 100 During this interval the central rotary insulator stack rotates with a uniform angular motion identical with the motion of the crank 62. The pin 56 which moves integrally with the insulator 2 therefore assumes the successive positions "b", "c", "d" 105 and "e" as indicated in Figure 6. During the interval of motion of the crank 62 from the position "a" to the position "b" the switch blade may remain stationary if there is even a slight force tending to hold the free end of the blade in engagement with its contact. Rotation of the insulator stack 2 merely stores energy in the spring 55. When the crank 62 reaches the position "b" 110 the contact 35 is out of engagement with the contact 40 as may be seen from Figure 6; hence there is no further tendency for the contact 35 to resist turning of the switch 115 120 125 130

blade 10. During this movement from the position "a" to the position "b" any ice or corrosion that may have tended to bind the contact 35 to the contact 40 was broken. 5 Further rotation of the central insulator stack 2 will therefore result in a turning of the switch blade 10 from the position shown in full lines, which is the closed position and also the position "b", through the successive positions "c", "d", and "e", the position "e" being the full switch open position of the blade. A similar action takes place 10 between the contact 40' (Figure 2) at the opposite end of the switch blade 10 and the corresponding contact mounted upon the insulator stack 15.

To close the switch the crank 60 (Figure 1) is rotated in the opposite direction thus 15 rotating the crank 62 in a counter-clockwise direction. The switch blade is moved to the full closed position and thereafter the contact 35 is further rotated into firm electrical contact with the arms of the contact 40.

20 Aluminum bronze is suggested for at least one of the cooperating contacts 35-40 because of its hardness and resistance to wear, also because of its springy quality and resistance to corrosion. Because of this 25 springy quality it is preferable to make the U-shaped contact 40 of aluminum bronze since the arms of this contact have a certain amount of resiliency in order that they may be spread apart by the contact 35 to establish 30 firm electrical engagement with that contact. When the contact 35 is out of engagement with the contact 40 the arms of this last mentioned contact are closer together than the distance between the opposite 35 faces 41-42 of the contact 35. As a result of this arrangement the springy quality of the contact 40 maintains a firm electrical engagement of this contact with the contact 35. The amount of springiness in 40 the contact 40 is appreciable due to the fact that this contact is secured to the end of the switch blade 10 at one of the arms of the contact, the other arm being free to permit an appreciable spreading. If both the 45 fork and the contact were made of copper the friction between them would be considerable, not only due to the increased coefficients of friction but mainly because of the binding action of the two films of copper 50 oxide that would form thereat. While the use of aluminum bronze contacts is preferred we do not wish to be limited to its use as copper or other metal may also be used.

55 Reference may now be had to Figure 7 wherein we show a single break switch embodying the principles of our invention. This switch includes an insulator stack 2 and an insulator stack 15 both of constructions similar to the corresponding stacks of

Figure 1. These insulators are mounted in the same manner as has been previously described in connection with the switch shown in Figure 1 and the rotary insulator 2 is rotated by means of a crank such as 60 in a 70 manner as previously described. The rotary insulator 15 is rotated from the insulator 2 in the same manner as is the corresponding insulator of Figure 1. This switch is in all particulars analogous to the left hand half 75 of the switch of Figure 1 differing therefrom in that we have provided a terminal upon the insulator stack 2 for receiving a line conductor, said terminal corresponding in function to the terminal 32 of Figure 1. 80 In this construction the switch blade 10' is mounted upon a blade holder 53' which is supported by the insulator 2 in a manner analogous to that shown in Figures 3 and 4. The spindle member which is mounted 85 on top of the upper insulator cap 6 of the insulator stack 2 extends beyond the switch blade and has a cylindrical member 31' corresponding to the cylindrical member 31 of Figure 1 mounted thereon. This cylindrical member is supported by the spindle but is freely rotatable with respect thereto. Hence when the insulator stack 2 and with it the supporting spindle is rotated the cylindrical member may remain stationary. Suitable 90 anti-friction bearing members are provided between the cylindrical member 31 and the spindle as is also the case with reference to the cylindrical member 31 of Figure 1. The member 31' is provided with a line 95 terminal 70 for receiving a line conductor, and a flexible lead 72 is provided for extending the circuit from the terminal 70 to the switch blade 10.

100 In compliance with the requirements of 105 the patent statutes we have herein shown and described a preferred form of our invention. The invention is, however, not limited to the precise construction herein shown, the same being merely illustrative. 110 What we consider new and desire to secure by Letters Patent is:

1. An electric switch including a pair of 115 rotary insulators, a contact member mounted on one of the insulators and including contacting portions on the opposite sides of the axis of rotation of the insulator, a cooperating switch blade pivotally mounted on the other insulator about a pivot coincident with the axis of rotation of said other insulator, and having a limited amount of motion with reference thereto, and means on the blade for establishing engagement with the portions of the contact on the opposite sides of the axis of rotation of the contact. 120

125 2. An electric switch including a pair of rotary insulators, a contact member mounted on one of the insulators and including contacting portions on the opposite sides of the axis of rotation of the insulator, a switch 130

blade mounted on the other insulator and movable in a plane at a substantial angle to the axis of rotation of the contact, means on the blade for establishing engagement 5 with the portions of the contact on the opposite sides of the axis of rotation of the contact, and means for opening the switch, said means including means for actuating first the contact and including a lost motion 10 connection for then actuating the blade.

3. An electric switch including a rotatable contact having contacting portions on opposite sides of the axis of rotation thereof, a switch blade movable at a substantial 15 angle to the axis of rotation of the contact into simultaneous engagement with both contacting portions, and means for opening said switch, said means including means for actuating first the contact and then the 20 blade.

4. An electric switch including a pair of cooperating contacts movable in the same plane, and an operating mechanism effective by a continuous motion to successively actuate both contacts.

5. An electric switch including a pair of cooperating contacts movable in the same plane, and an operating mechanism effective by a continuous motion to actuate first one 30 contact then the other contact, there being a lost motion between the operating mechanism and at least one of the contacts.

6. An electric switch having a relatively short switch contact and a relatively long 35 switch blade, and means for rotating the blade and the contact about parallel axes, said contact and said blade engaging one another at two points on opposite sides of the axis of rotation of the contact.

40 7. An electric switch including a supporting base, a rotatable bearing mounted thereon, an insulator mounted on the rotatable portion of the bearing, a switch blade mounted on the insulator and rotated thereby, a pair of spaced bearings mounted on the base on opposite sides of the first mentioned bearing, insulators mounted on each of the rotatable elements of the last mentioned bearings, and contacts mounted on 45 the last mentioned insulators and adapted to be engaged by the blade, each of the contacts including contacting portions on the opposite sides of the axis of rotation thereof, and said blade including contacting members 55 for engaging both of the contacting portions of each of the contacts.

8. An electric switch including a supporting base, a rotatable bearing mounted thereon, an insulator mounted on the rotatable 60 portion of the bearing, a switch blade mounted on the insulator and rotated thereby, a pair of spaced bearings mounted on the base on opposite sides of the first mentioned bearing, insulators mounted on each 65 of the rotatable elements of the last men-

tioned bearings, contacts mounted on the last mentioned insulators and adapted to be engaged by the blade, means for rotating the first mentioned insulator, and a link-work extending from the rotating mechanism for rotating each of the other two insulators, said link-work including a crank adjacent each of the two last mentioned insulators and links for rotating the cranks, said links making an angle substantially 70 greater than 90° with their respective cranks when the switch is in the closed position.

9. An electric switch including a supporting base, a rotatable bearing mounted thereon, an insulator mounted on the rotatable portion of the bearing, a switch blade mounted on the insulator and rotated thereby, a pair of spaced bearings mounted on the base on opposite sides of the first mentioned bearing, insulators mounted on each of the rotatable elements of the last mentioned bearings, contacts mounted on the last mentioned insulators and adapted to be engaged by the blade, each of the contacts including contacting portions on the opposite sides of the axis of rotation thereof, and said blade including contacting members for engaging both of the contacting portions of each of the contacts, means for rotating the first mentioned insulator, and a link-work extending from the rotating mechanism for rotating each of the other two insulators, said link-work including a crank adjacent each of the two last mentioned insulators and links for rotating the cranks, said links making an angle substantially 75 greater than 90° with their respective cranks when the switch is in the closed position.

10. An electric switch including a supporting base, a rotatable bearing mounted thereon, an insulator mounted on the rotatable portion of the bearing, a switch blade mounted on the insulator and rotated thereby, a pair of spaced bearings mounted on the base on opposite sides of the first mentioned bearing, insulators mounted on each of the rotatable elements of the last mentioned bearings, contacts mounted on the last mentioned insulators and adapted to be engaged by the blade, and means for successively rotating the contacts and the blade 100 to open the switch.

11. An electric switch including a supporting base, a rotatable bearing mounted thereon, an insulator mounted on the rotatable portion of the bearing, a switch blade mounted on the insulator and rotated thereby, a pair of spaced bearings mounted on the base on opposite sides of the first mentioned bearing, insulators mounted on each of the rotatable elements of the last mentioned bearings, contacts mounted on the last mentioned insulators and adapted to be 115 120 125 130

- engaged by the blade, and means for rotating the contacts and the blade to open the switch, said means including a lost motion connection for permitting the blade to remain stationary during a predetermined substantial portion of the switch opening movement of the contacts. 70
12. An electric switch including a supporting base, a rotatable bearing mounted thereon, an insulator mounted on the rotatable portion of the bearing, a switch blade mounted on the insulator and rotated thereby, a pair of spaced bearings mounted on the base on opposite sides of the first mentioned bearing, insulators mounted on each of the rotatable elements of the last mentioned bearings, contacts mounted on the last mentioned insulators and adapted to be engaged by the blade, each of the contacts including contacting portions on the opposite sides of the axis of rotation thereof, and said blade including contacting members for engaging both of the contacting portions of each of the contacts, and means for successively rotating the contacts and the blade to open the switch. 75
13. An electric switch including a supporting base, a rotatable bearing mounted thereon, an insulator mounted on the rotatable portion of the bearing, a switch blade mounted on the insulator and rotated thereby, a pair of spaced bearings mounted on the base on opposite sides of the first mentioned bearing, insulators mounted on each of the rotatable elements of the last mentioned bearings, contacts mounted on the last mentioned insulators and adapted to be engaged by the blade, each of the contacts including contacting portions on the opposite sides of the axis of rotation thereof, and said blade including contacting members for engaging both of the contacting portions of each of the contacts, and means for rotating the contacts and the blade to open the switch. 80
14. An electric switch including a rotatable insulator, a switch blade pivotally mounted on the insulator at the axis of rotation thereof whereby upon the initial rotation of the insulator the blade remains stationary, spring means for urging the blade to move as a unit with the insulator, a second rotary insulator, and a contact mounted thereon and adapted to be engaged by the blade. 85
15. An electric switch including a rotatable insulator, a switch blade pivotally mounted on the insulator at the axis of rotation thereof whereby upon the initial rotation of the insulator the blade remains stationary, spring means for urging the blade to move as a unit with the insulator, a second rotary insulator, a contact mounted thereon and adapted to be engaged by the blade, and a mechanical connection between the two insulators whereby upon rotation of one insulator the other is rotated therewith. 90
16. An electric switch including a rotatable actuating insulator, a switch blade pivotally mounted thereon and actuated thereby, the pivot of the switch blade being coincident with the axis of rotation of the insulator, whereby upon the initial rotation of the insulator the blade may remain stationary, and spring means between the blade and the insulator tending to maintain them in a predetermined angular position with respect to one another. 95
17. An electric switch including a blade, a contact adapted to be engaged thereby, and means for successively rotating the two about parallel axes. 100
18. An electric switch including a blade, a contact adapted to be engaged thereby, and means for successively rotating first the contact and then the blade, the blade and the contact being rotated about parallel axes. 105
19. An electric switch including a support, a rotatable bearing mounted thereon, an insulator mounted on the rotatable portion of the bearing, a switch blade mounted on the insulator and rotated thereby, a bearing mounted on the support and spaced from the first mentioned bearing, an insulator mounted on the rotatable element of the last mentioned bearing, a contact mounted on the last mentioned insulator and adapted to be engaged by the blade, and means for successively rotating the contact and the blade to open the switch. 110
20. An electric switch including a pair of spaced rotatable insulators, a contact mounted on one of the insulators, a cooperating blade pivotally mounted on the other insulator about an axis coincident with the axis of rotation of said other insulator whereby the blade may remain stationary during rotation of its supporting insulator, and means for opening the switch, said means comprising means for simultaneously rotating both insulators whereby the blade initially remains stationary while the contact is rotated, and stop means effective after a predetermined rotation of the blade supporting insulator for thereafter rotating the blade with its insulator. 115
21. A switch including a pivotally mounted contact, a blade movable into and out of engagement with the contact, means including a rotatable member for supporting and actuating the blade, said blade being pivotally supported on said member about a pivot coincident with the axis of rotation of said member, means for rotating the contact and the blade supporting member, and means 120

- 130

effective after a predetermined rotation of the blade supporting member for forcing the blade to thereafter move with said member.

5. In witness whereof, we hereunto subscribe our names this 22nd day of April, 1930.

ALFRED ALSAKER.
WELDON O. HAMPTON.
CHARLES A. KOERNER.
